CLAIM

The ornamental design for a medical reclining chair, as shown.

DESCRIPTION

FIG. 1 is a perspective view of a medical reclining chair according to the present invention, showing the chair in the upright position;

FIG. 2 is a front elevation view of the reclining chair in FIG. 1;

FIG. 3 is a side elevation view of the reclining chair in FIG. 1;

FIG. 4 is rear elevation view of the reclining chair in FIG. 1;

FIG. 5 is a top elevation view of the reclining chair in FIG. 1;

FIG. 6 is a bottom elevation view of the reclining chair in FIG. 1;

FIG. 7 is a perspective view of the reclining chair in FIG. 1, showing the chair in the reclined position; and,

FIG. 8 is a perspective view of the reclining chair in FIG. 1 showing the chair in the a further reclined position.

The broken line showing of the wheels, side panels, and back frame is for illustrative purposes only and forms no part of the claimed design.
